UNITED STATES PATENT OFFICE.

JOHN W. KUMMER, OF GOLDFIELD, NEVADA.

CURTAIN-FIXTURE.

No. 923,050.

Specification of Letters Patent.

Patented May 25, 1909.

Application filed November 4, 1908. Serial No. 461,022.

To all whom it may concern:

Be it known that I, JOHN W. KUMMER, a citizen of the United States, residing at Goldfield, in the county of Esmeralda and State 5 of Nevada, have invented certain new and useful Improvements in Curtain-Fixtures, of which the following is a specification, reference being had therein to the accompanying drawing.

10 My invention relates to curtain fixtures, and the essential objects thereof are to provide a device of this character which is entirely automatic in operation; to furnish a curtain fixture which is simple in construction and arrangement, and may be operated with facility; and to provide means that will replace the ordinary well known type of curtain fixture and the appurtenant pawl and ratchet mechanism, and in this manner dispense with the irregularities with which one is confronted when attempting to secure an adjustment of the curtain.

To the accomplishment of the recited objects and others coördinate therewith, the 25 preferred embodiment of my invention resides in that construction and arrangement of parts hereinafter described, illustrated in the accompanying drawings, and embraced within the scope of the appended claims.

30 In said drawings: Figure I is a front elevation of the curtain fixture embodying my invention, and Fig. II is an elevation of the same. Fig. III is a fragmentary longitudinal sectional view of the auxiliary reel. Fig. 35 IV illustrates a blank of one of the sections of the reel. Fig. V is a detail perspective view of one of the reel sections just previous to its application to the terminal of the curtain rod. Fig. VI is an end elevation of the 40 curtain rod, showing the position assumed by the reel. Fig. VII is a transverse sectional view of the guide rod and coöperating runner clamp, and Fig. VIII is a detail perspective of the runner clamp.

45 Referring more particularly to the drawings for a detail description of my invention, the numeral 5 designates a window frame which is provided adjacent its upper end with the usual brackets (6) for supporting the 50 curtain pole (7). On one of the distal ends of the curtain pole I mount what might be termed an auxiliary reel or drum which comprises a pair of members, each member presenting an annular flanged body portion (8) 55 and diametrically disposed, integrally formed projections (9), which are designed to be flexed

as to have a portion thereof lie contiguous the outer side of the said body (8), the remaining portion being arranged at right angles thereto and having apertures (10) for the reception 60 of any suitable fastening means, such as 11. As clearly exhibited in Fig. VI of the drawings, the terminal of the curtain rod (7) is squared, as at 12, to form a convenient bearing for the projections (9) and at the same time 65 preclude any rotary displacement of the sections, considered as an entirety, independent of the movement of the curtain rod. This reel, as just described, is devised to accommodate a selvaged band (13), the outer ex- 70 tremital portion thereof being suitably fastened, as at 14, to the oblong slot (15) of the upwardly curved lip of the runner clamp (16) which has movement longitudinal of the 75 guide rod (17), the latter being mounted upon the conoidal shaped supports (18) which are in turn secured to the window frame (5) in any convenient manner.

In operation, the clamp (16) is released from engagement with the rod (14) by an 80 appropriate manipulation of the thumb screw (19) and, owing to the weight of the curtain (20), the same will gravitate to any desired position, this gravitation of the curtain being accelerated by providing a slightly 85 heavier bottom cross rod at 21. Now when a reverse adjustment of the curtain is required it only becomes necessary to lower the clamp (16) along the rod (17). Subsequent each operation the thumb screw (19) 90 is adjusted so as to maintain the curtain in proper relation to the window.

What I claim as new is:—

1. The combination with a roller and a curtain, of an auxiliary reel mounted on said roller, a guide rod, a runner clamp movable along the entire length of said guide rod and having a slotted lip, and a band carried by said reel and having connection with the slot in said lip. 100

2. The combination with a roller and a curtain, of an auxiliary reel comprising a pair of members constituting flanges, said members being provided with diametrically disposed, apertured attaching extensions 105 bent upon said members and projecting laterally therefrom at right angles, a band arranged intermediate said members, and means for adjusting said band to raise or lower the curtain. 110

3. The combination with a roller and a curtain, of an auxiliary reel comprising a

pair of members constituting flanges, said members being provided with diametrically disposed, apertured attaching extensions bent upon said members and projecting laterally therefrom at right angles, said flanged members being arranged in spaced relation upon one terminal of the roller with their apertured attaching extensions in alternation, a band arranged intermediate said members,

and means for adjusting said band to raise or lower the curtain.

In testimony whereof I hereunto affix my signature in presence of two witnesses.

JOHN W. KUMMER.

Witnesses:

A. MACKENZIE,
RAY TWILEGAR.
